DISPLAY CARD, PARTICULARLY FOR PIPE
STEMS

Otto Brunner, Jackson Heights, N. Y., assignor to
Henry Leonard & Thomas, Inc., Ozone Park,
N. Y., a corporation of New York

Application October 23, 1941, Serial No. 416,191

4 Claims. (Cl. 211—60)

This invention relates to display cards, and more particularly to a display card for the display and sale of stems for tobacco pipes.

The primary object of my invention is to generally improve display cards. Such cards have heretofore been made with wires or cords to hold the individual articles being displayed. This adds to the cost of manufacturing the display card, and is undesirable because the wire or cord may be destroyed in removing the article, thus making it impractical to return the same to the card. Some cards have been made with spring clips, but these tend to mar the article being displayed, and greatly increase the cost of the card. The use of rubber-covered spring clips is still more costly and is relatively unsightly.

One primary object of the invention is to overcome the foregoing difficulties and to provide an improved display card which may be manufactured inexpensively, in comparatively few operations, and wholly out of cardboard or like material. Another object is to provide a display card which may be folded into flat condition for storage or shipment.

To the accomplishment of the foregoing general objects and other more specific objects which will hereinafter appear, my invention consists in the display card elements and their relation one to the other as hereinafter are more particularly described in the specification and sought to be defined in the claims. The specification is accompanied by a drawing, in which:

Fig. 1 is a perspective front view of a display card embodying features of my invention;

Fig. 2 is a perspective rear view of the same;

Fig. 3 is a rear elevation of the display card when folded flat;

Fig. 4 is a horizontal section through the display card taken approximately in the plane of the line 4—4 of Fig. 3, with the display card folded part way;

Fig. 5 is a horizontal section taken approximately in the plane of the line 5—5 of Fig. 2;

Fig. 6 is a horizontal section taken approximately in the plane of the line 6—6 of Fig. 2;

Fig. 7 is a horizontal section taken approximately in the plane of the line 7—7 of Fig. 3; with the display card folded part way; and

Fig. 8 is a horizontal section taken approximately in the plane of the line 8—8 of Fig. 3, with the display card folded part way.

Referring to the drawing, and more particularly to Fig. 1, the display card comprises a main display board 12 having a plurality of support columns or strips 14 projecting from the front thereof. These strips pass through slots 16 in the main board 12, and are formed integrally with an easel structure on the back of the main board 12. In Fig. 1, the left-hand strip 14 is broken away at the bottom to expose slot 16.

The easel structure is shown in Figs. 2 through 8 of the drawing. It is generally in the form of a large hollow column which is rectangular in section. At its upper end it comprises side walls 18 connected by a back wall 20 which is spaced from the main board 12. The forward edge of side walls 18 are turned inwardly to form tabs or strips 22 which are cemented to main board 12.

At an intermediate point the side walls 18 are connected by another section of back wall 24. Between the back wall sections 20 and 24, a part of the material is folded forwardly and downwardly to provide a locking strip 26, the forward edge of which is notched at 28 (Figs. 3 and 6) to interlock with the side walls 18, thereby holding the parts in perpendicular relation, as is best shown in Fig. 6. The side walls are cut away at 30 (Figs. 2 and 3) to accommodate the locking strip 26, and to provide a part of the material for the same, specifically, the ends of the same.

Below the part 24 the easel has no back wall, the material being cut away to widen the side walls, and thus providing relatively widened feet 32. This adds stability to the easel and display card, without necessitating too deep a column for the easel structure throughout its length.

At the lower end of the easel the forward edges of the side walls or feet 32 are turned inwardly to form tabs or strips 34 which are permanently cemented to the back of the main board 12.

It will be evident that this easel structure may be folded flat against the back of the main board by turning the locking strip 26 upwardly to the position shown in Fig. 3, and then pushing the structure sidewardly. The condition of the parts when moved part way toward flat condition is illustrated in Figs. 4, 7, and 8, while in Fig. 3, the parts have been moved all the way to flat condition.

Between the upper folded and cemented strips 22 and the lower folded and cemented strips 34, the side walls 18 of the easel structure are unfolded and project forwardly through the main board 12 to provide the desired support strips 14.

These are apertured to frictionally receive the pipe stems. In the present case each pipe stem 40 is provided with a metal fitting or tenon 42, and the holes 44 through the support strip 14 are dimensioned to rather snugly frictionally receive the tenon 42. In the specific case here illustrated, there are six holes in each support strip, thus adapting the same to receive and display twelve pipe stems, these being disposed with the tenons pointed toward one another and the bits pointed outwardly. The frictional fit is such that the bits may be removed, examined, and returned, if desired.

The slots 16 through the main board 12 are preferably made with ample clearance to facilitate sideward folding of the support strips to

gether with the easel. This clearance is disposed predominantly at one side of the support strip. Thus in Fig. 6, it will be seen that the excess width of slot 16 is disposed at the right of the support strips 14. The same applies to Fig. 2. In Fig. 1 the structure is viewed from opposite direction, hence the excess slot dimension is at the left of the support strips. In any case, this excess is in one direction for both slots, and this helps accommodate folding of the easel and support strips in one direction, as will be seen from inspection of Fig. 7.

Moreover, the main board 12 is preferably provided with short horizontal cuts 46 (Figs. 1 and 2) at the upper and lower ends of the slots 16. These cuts permit the material of the main board to yield slightly when the display is folded flat. This is illustrated in Fig. 7 by the slight inward turning of the main board at 48, and the slight outward turning of the main board at 50.

The upper part of the main board 12 may be cut to any desired configuration, as is illustrated at 52, and may be provided with appropriate advertising or/and illustrative matter.

It is believed that the construction and method of using, as well as the advantages of my improved display card will be apparent from the foregoing detailed description thereof. The entire display card is made of only two pieces of cardboard. There is no need for cords, wires, or spring clips. There is no marring of the stems, and they are displayed over their entire length. All of the work may be performed by the lithographing company which prints the display. The card may be folded flat for compact storage and shipment. The pipe stems may be packaged and shipped separately. The storekeeper readily sets up the display card and inserts the pipe stems. These are easily removed for inspection and sale, and may be returned to the card if not sold.

It will be apparent that while I have shown and described my invention in a preferred form, many changes and modifications may be made in the structure disclosed without departing from the spirit of the invention, as sought to be defined in the following claims.

I claim:

1. A display card comprising a main display board made of cardboard or the like, means on the back of said board to support the same in substantially upright position, said means comprising a single piece of cardboard or the like cut and bent to form side walls connected by a rear wall, part of the inner edges of the side walls being turned to form flaps which are cemented to the back of the main board, the remainder of the inner edges of the side walls projecting straight forward through receptive slots in the main board, to provide holder strips which are cut to receive a plurality of the objects to be displayed, the back wall being cut away at the bottom to form extensions of both of the side walls which extensions act as feet to support the display board with increased stability, another part of the back wall and side walls being cut away and folded to horizontal position and notched to interlock with the side walls in order to hold the assembly in desired position.

2. A display card for pipe stems, said card comprising a main display board made of cardboard or the like, means on the back of said board to support the same in substantially upright position, said means comprising a single piece of cardboard or the like cut and bent to form side walls connected by a rear wall, the 75

inner edges of the side walls near the top and bottom being turned to form flaps which are cemented to the back of the main board, the main board being slotted at the side walls and said walls being extended through said slots between the top and bottom flaps to provide holder strips which project in vertical position from the front of the display board, said holder strips being perforated to frictionally receive a plurality of pipe stems to be displayed, the rear wall being parallel to the main board, and the side walls being parallel to one another, and the slots in the main board being wider than the thickness of the holder strips, so that said support means and holder strips may be folded flat against the main board when not in use.

3. A display card for pipe stems, said card comprising a main display card made of cardboard or the like, means on the back of said board to support the same in substantially upright position, said means comprising a single piece of cardboard or the like cut and bent to form side walls connected by a rear wall, the inner edges of the side walls near the top and bottom being turned to form flaps which are cemented to the back of the main board, a part of the back wall and side walls being cut away and folded to horizontal position and notched to interlock with the side walls in order to hold the assembly in desired position, the main board being slotted at the side walls and said walls being extended through said slots between the top and bottom flaps to provide holder strips which project in vertical position from the front of the display board, said holder strips being perforated to frictionally receive a plurality of pipe stems to be displayed, the rear wall being parallel to the main board, and the side walls being parallel to one another, and the slots in the main board being wider than the thickness of the holder strips, so that said support means and holder strips may be folded flat against the main board when not in use.

4. A display card for pipe stems, said card comprising a main display card made of cardboard or the like, means on the back of said board to support the same in substantially upright position, said means comprising a single piece of cardboard or the like cut and bent to form side walls connected by a rear wall, the inner edges of the side walls near the top and bottom being turned to form flaps which are cemented to the back of the main board, the back wall being cut away at the bottom to form extensions of the side walls which act as feet to support the display board with increased stability, another part of the back wall and side walls being cut away and folded to horizontal position and notched to interlock with the side walls in order to hold the assembly in desired position, the main board being slotted at the side walls and said walls being extended through said slots between the top and bottom flaps to provide holder strips which project in vertical position from the front of the display board, said holder strips being perforated to frictionally receive a plurality of pipe stems to be displayed, the rear wall being parallel to the main board, and the side walls being parallel to one another, and the slots in the main board being wider than the thickness of the holder strips, so that said support means and holder strips may be folded flat against the main board when not in use.
